UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR RAILWAY-CARS.

1,341,149.

Specification of Letters Patent. Patented May 25, 1920.

Application filed June 10, 1915. Serial No. 33,277.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

One of the objects of my invention is to provide a railway car draft rigging of high capacity and efficient operation.

Another object is to provide a draft rigging having resilient stop members.

Further objects will appear from the description of my invention following herein.

In the drawings forming a part of this specification, Figure 1 is a side elevation of a draft rigging embodying my invention; Fig. 2 is a side elevation of one of the stop members partly in vertical longitudinal section on line 2—2 of Fig. 3; Fig. 3 is a plan view partly in horizontal section, taken on line 3—3 of Fig. 1; Fig. 4 is a cross section taken on line 4—4 of Fig. 1.

Referring to the drawings, the numerals 5—5 indicate draft members or parts of the car frame to which the draft rigging is applied. 6—6 indicate stop members or cheek plates, hereinafter more particularly described. A draft gear 7, which may be of any suitable type, is mounted between the stop members. The particular type shown in the drawing is a friction gear comprising a casing 8 having friction members 9 and springs 10 associated therewith. The rear end of the casing 11 constitutes the rear follower, which, for convenience, we will hereinafter refer to as the rear follower. A front follower 12 serves its usual function, and the followers and springs are inclosed within a yoke 13, which may be of any suitable type, the yoke being suitably secured at its forward end to the draw-bar 14. The yoke and draft gear are supported between the draft members by means of the saddle 15, which is suitably secured at its ends to the draft members, as, for instance, by the bolts 16—16. The stop members 6 are secured in opposed relation to the inner faces 55 of the draft members by suitable means,

preferably the rivets 17—17. The stop members are counterparts of each other, and we therefore will describe only one. Each stop member 6 comprises a stationary portion 18 rigidly secured to the adjacent draft member, and a movable portion 19 adapted to co-act therewith. The stationary portion 18 comprises a web 20 having transverse flanges 21 and 22 at the front and rear ends thereof, respectively forming front and rear shoulders adapted to limit the movements of the movable portion 19 of the stop member. The stationary portion 18 of the stop member is also provided with vertically spaced-apart upper and lower in-turned flanges 23 and 24, respectively forming a groove or guide within which the movable portion 19 of the stop member is partially received. Within the groove between the front and rear shoulders 21 and 22 is mounted, at intervals, a plurality of upper and lower stops 25 and 26 respectively, the said upper stops 25 being preferably integral with the adjacent web 20 of the stationary member 18, and the lower stops being preferably integral with the lower flange 24 and the said web 20. The stops 25 and 26 are suitably spaced-apart vertically to permit reciprocating movement between them of stops upon the movable member 19 to be hereinafter described. In the intervals 27 between the upper stops 25 and the intervals 28 between the lower stops 26 are mounted springs 29, the said springs being preferably flat plates grouped as illustrated in Fig. 2 of the drawings, and extending vertically at intervals throughout the length of the stop member, between the shoulders 21 and 22 of the stationary member 18. The stops 25 and 26 are each preferably curved, as shown at the numeral 30, to permit the flexing of the springs 29 in either direction while the ends of said springs are held between the stops hereinbefore described. The movable member 19 of each stop member consists of a plate having a vertical longitudinally extending web 31, an upper transverse outwardly extending flange 32 which is received within a longitudinally extending way 33 between the upper edges of the stops 25 and the flange 23 of the stationary member 18. On the inner face of the web 31 are arranged, at intervals corresponding substantially with the intervals between the upper stops 25 and the lower 110

stops 26 of the stationary member 18, stops 34, which are preferably integral with the web 31, the said stops in preferable construction having front and rear convex bearing faces, as indicated at the numerals 35-35 in Fig. 2 of the drawings. The stops 34 are suitably spaced apart longitudinally to receive between them each a set of springs 29. In preferable construction, therefore, 10 the stops 34 of the movable member 19 equal in number the stops 25 or the stops 26 of the stationary member 18. The movable member 19 is provided on its face opposed to the draft gear 7 with a rear stop shoulder 38, a front stop shoulder 39, and limiting stop shoulders 40 and 41.

On rearward movement of the draw-bar, the draft gear is stopped by the rear stop shoulders 38 of the movable portion 19 of 20 the stop members, the draw-bar thrust being transmitted from the movable members to the stationary members 18 through the series of resisting springs 29, which are flexed rearwardly by the relative rearward movement of the stops 34 on the movable member 19, and are held at their ends by the stops 25 and 26 upon the stationary member 18. Upon full compression of the draft gear, the rearward movement of the front follower 30 lower is limited by its engagement against the limiting stop shoulders 40. If the compression resisting power of the combined springs 29 is arranged so as to be greater than that of the draft gear, then with a 35 sufficiently heavy rearward thrust of the draw-bar to close the draft gear, the further rearward movement of the draw-bar in reference to the draft members will be permitted until the entire shock absorbing capacity of the resilient stop members has 40 been exhausted.

On forward movement of the draw-bar, the draft gear is stopped at its forward end by the front stop shoulders 39 through the 45 medium of the front follower 12, and the forward movement of the draw-bar is resisted by the draft gear 7 and also by the resilient stop members, in a manner similar to that described in connection with the 50 rearward movement of the draw-bar. The forward movement of the draft gear is limited by the limiting stop shoulders 41, which in the specific type of draft gear illustrated in the drawings engage the forward edges 55 45 of the spring case 46 of the draft gear. The further action is similar to that on rearward movement of the draw-bar, and, as will be obvious, will be in some measure dependent upon the relative compression resisting capacity of the resilient stop members and the draft gear.

It will be apparent that, with stop members, which are within themselves resilient and draw-bar resisting, a high spring resistance in addition to the resistance af-

fords by the draft gear proper, may be had, and also by the interposition of the resilient stop members between the draft gear and the underframe of the car, the total draw-bar movement may be increased over the 70 movement of the draft gear. Thus, with my invention, not only is a high capacitated draft rigging afforded, but the shock absorbing capacity of draft gears can be highly supplemented by the use of my resilient stop 75 members, and draft gears with comparatively short movement may by the use of the said resilient stop members afford the draw-bar a longer movement when conditions of railroad service make such longer 80 movement desirable. It is also apparent that by varying and changing the size and shape of the stops 25, 26 or 34, the springs 29 may be brought into action in series or one after another. 85

I claim:—

1. In a stop member for railway car draft rigging, a grooved stationary member having shoulders on its inner face, a movable member having shoulders on its outer face 90 to operate therein, and springs interposed between the shoulders of the movable member and the shoulders of the stationary member.

2. In a draft rigging for railway cars, a 95 stop member comprising a stationary portion having upper and lower stop shoulders, a movable portion having stop shoulders adapted to pass between the upper and lower shoulders of the stationary portion, 100 and springs interposed between the stop shoulders of the movable portion and the stop shoulders of the stationary portion.

3. In a draft rigging for railway cars, a stop member having upper and lower 105 spaced-apart stop shoulders, springs held between said shoulders, and a movable member having shoulders engaging between the springs.

4. In a railway car draft rigging, a stop 110 member comprising a stationary portion having upper and lower stop shoulders, a movable portion having stop shoulders, springs interposed between the stop shoulders of the movable portion and the shoulders of the stationary portion, the movable portion being provided with a flange, and the stationary portion being provided with a groove extending longitudinally above the stationary stop members to receive said 115 flange.

5. In a railway car draft rigging, a stop member comprising a stationary portion, a plurality of spaced-apart vertically arranged springs therein, and a movable portion having shoulders on its outer face adapted to engage between said springs. 125

6. In a railway car draft rigging, a stop member having a stationary portion, spaced-apart vertically arranged springs therein, a 130

movable portion, the movable portion having shoulders on its outer face adapted to engage between said springs, the stationary portion being provided with shoulders on its 5 inner face adapted to hold the ends of said springs.

7. In a draft rigging for railway cars, the combination with draft sills, of stop members rigidly secured to said sills other 10 stop members yieldingly mounted on the inner faces of the first named stop members, yieldingly mounted stop members being provided on their inner faces with stops for co-operation with the followers of a gear, and 15 a draft gear mounted between the sets of stop members and having followers coöperable with said stops.

8. In a draft rigging for railway cars, the combination with a gear having followers, of draft sills, and means coacting 20 with the followers of said draft gear and mounted on said sills, said means comprising two castings rigidly secured to the inner faces of the sills, two additional castings 25 mounted on the inner faces of the first named castings, and springs of high capacity interposed between the two sets of castings whereby, after the actuation of the gear, said high capacity springs come into 30 play to provide additional cushioning capacity.

9. A stop member for railway draft riggings, comprising two castings relatively 35 longitudinally movable, one of said castings having an upper series of shoulders and a lower series of shoulders spaced therefrom, the other casting having a centrally located series of shoulders movable longitudinally between said upper and lower sets of shoul-

ders, and springs interposed between the sets 40 of shoulders to thereby provide a cushion for resisting relative movement between the two castings.

10. A stop member for railway draft riggings, comprising two castings relatively 45 longitudinally movable, one of said castings having an upper series of shoulders and a lower series of shoulders spaced therefrom, the other casting having a centrally located series of shoulders movable longitudinally 50 between said upper and lower sets of shoulders, and springs interposed between the sets of shoulders to thereby provide a cushion for resisting relative movement between the two castings, all of said shoulders having 55 curved faces to facilitate the action of the cushioning means.

11. A stop member for railway draft riggings comprising, two plates and a series 60 of springs, said two plates extending parallel to each other, one over the other and provided with coöperating sets of shoulders on their adjacent opposed faces, the springs being interposed between said shoulders and adapted to yieldingly resist relative movement 65 between the plates, one of such plates being adapted for rigid attachment to a draft sill and the other plate, on its side remote from said springs, having shoulders arranged for coöperation with followers of 70 a shock absorbing mechanism.

In witness that I claim the foregoing I have hereunto subscribed my name this 27th day of May, 1915.

JOHN F. O'CONNOR
